UNITED STATES PATENT OFFICE.

HAROLD A. LOMAX, OF ASPINWALL, PENNSYLVANIA.

PROCESS OF CASTING ROLLS AND THE LIKE.

1,242,827.

Specification of Letters Patent.

Patented Oct. 9, 1917.

Application filed August 21, 1916. Serial No. 115,998.

To all whom it may concern:

Be it known that I, HAROLD A. LOMAX, a citizen of the United States, residing at Aspinwall, in the county of Allegheny and State of Pennsylvania, have invented certain new and useful Improvements in Processes of Casting Rolls and the like, of which the following is a specification.

My invention consists in an improved method or process of casting rolls for rolling mills and other similar articles.

In rolls of the type used in reducing metal in rolling mills, they are ordinarily provided with a main roll body, journal necks, and terminal wabbler connecting portions cast in one piece, and requiring considerable finishing treatment to form the wabbler terminals. In their usual form these terminals are provided with a plurality of laterally extending wings and intervening recesses for engagement with the connecting wabbler, and are ordinarily machined down from cylindrical blank casting entailing considerable expense. A common cause of failure in rolls is also due to imperfections in the metal, due to shrinkage and other causes incidental to making the entire roll in one cast.

My invention has in view to provide means for casting a roll in such a manner as to cast the wabbler terminals and, if desired, portions of the journal necks, by supplying additional hot metal during or supplemental to the main casting operation, whereby to supplement the main body, and compensate for shrinkage and to cast the wabbler terminal with a sinkhead extension, within suitable casting mechanism, in the manner more fully hereinafter described.

In the drawings which illustrate different forms of mechanism for molding the journal and wabbler portion of one end of the roll, in vertical casting thereof,—

Figure 1 shows portions of a sand molding flask, together with a cast blank and the neck and wabbler forming mold and metal supply means.

Fig. 2 is a plan view of Fig. 1, showing the mold before casting.

Figs. 3 and 4, and 5 and 6 respectively are corresponding views illustrating modified constructions adapted to carry out the invention.

The roll A, which is usually cast vertically within the sand mold 2 of flask 3 of

any suitable construction, is usually formed from upwardly flowing metal supplied by a lower conduit 4 leading to a supply exterior of the mold. The molten metal as it rises carries impurities and surplus metal to the top, a large proportion of such surplus metal being ordinarily utilized at the upper end of the mold to provide against shrinkage, piping, and other well-known contingencies.

The journal portions of the roll 5, 5, are molded within the sand mold of the flask, as in ordinary casting operations, as is also the lower wabbler terminal 6. The upper wabbler terminal 6^a is, however, cast considerably longer than the required length, with the wabbler-engaging wings continuous to the top, as in Fig. 1, whereby to provide at its upper portion additional metal as required by absorption into the main body of the roll, its upper neck and upper wabbler, as the roll gradually cools and shrinkage takes place.

In ordinary casting from below such surplus metal becomes very considerably chilled, thereby preventing free flow for compensation of shrinkage and tending to the formation of a central "pipe," due to shrinkage and cooling of the mass. The upper portion of the metal usually carries with it impurities and imperfect metal, which should ordinarily be thrown sufficiently high to be cut off as waste.

My invention consists in supplementing the main body of metal, after the main cast is made, with additional fresh metal from above, and in introducing such fresh metal into the upper wabbler and neck portion, whereby to renew the same, with sufficient surplus to carry all impure metal, and upper waste or surplus portions to the top, and whereby to supply and maintain the supplemental renewing metal at a considerably higher temperature than that of the already cast roll, thereby maintaining its fluidity sufficiently long to insure the formation of an absolutely solid homogeneous neck and wabbler section and the maintenance of a higher degree of heat at such portions of the wabbler at the end of the cast.

I also accomplish the formation of the upper wabbler by such terminal molding operation in practically finished form, so that it is molded into shape corresponding

approximately to that of the lower wabbler, the wabbler extension surplus being later removed, as is also the surplus sinkhead portion or portions.

- 5 For the purpose of thus forming the upper portion of the roll, I provide a supplemental molding core 7, preferably in two parts, extending across the upper central portion of the main molding body 2, and 10 resting thereon by lateral extensions 8, providing between its outer portion and the main molding body of sand intervening semi-cylindrical clearance portions for the supplemental supply for the sinkheads 9.
- 15 The supplemental metal is poured into these molding cavities from above, either into the central wabbler cavity or the outer cavities, after the main roll has been cast up to, say, the level b, b , corresponding approximately to the desired length of the 20 wabbler, or higher. The additional hot metal flows into and amalgamates with the already cast portion of the wabbler and neck, carrying with it upwardly any impurities to the top portion and providing the upper supplemental reservoir supply and eventual waste portions as to both the 25 sinkhead and wabbler elements above, say, the line b, b , as to the wabbler, to any necessary extent.

In Figs. 3 and 4 the arrangement of the mold portions, outer sinkheads, and wabbler extension sinkhead is substantially the same as already described, except that the pattern 30 for forming the sinkhead cavity should be so constructed as to provide at about the terminal or slightly beyond the end of the wabbler section 6^a rounded or concaved terminals of the spaces between the wabbler 35 wings, as indicated at 6^b, whereby to provide a cylindrical extension 6^{aa} within the core 7^a for ease of flow and ample supply of feed metal, and particularly to avoid cracks or fissures in shrinking, by the prevention of 40 any sharp or rectangular angles.

The arrangement of the sinkhead mold cavities of the other parts are as already described.

In Figs. 5 and 6, the general arrangement 45 of the roll casting mold is substantially as already described and identified by similar numerals, except that the outer sinkhead extensions 9^c are extended upwardly beyond the main roll body A of the same, or slightly 50 less diameter, continuously around, forming a neck section considerably larger than necessary, and adapted to be turned off to provide the upper neck, as indicated by the dotted line 5^c. The sand core 7^c is formed 55 and located in substantially the same way, and the operation as already described carried out, the surplus metal being turned 60 away in final treatment of the roll for use.

It will be understood that various means

or modified adaptations of the invention as 65 to the particular mechanism for molding the parts, controlling the degree of addition of surplus metal, the percentage of waste, or various other features or details incident to carrying out the invention may be variously 70 changed or modified by the molder or foundry practice employed without departure from the scope of the invention.

The advantages of forming a practically finished wabbler extension and the resulting 75 reduction in the cost and time for cutting away the surplus metal and the several other advantages of the invention will be understood and appreciated by those familiar with the art.

Having described my invention, what I claim is:

1. In the manufacture of rolls of the class described, the formation of a main roll body, neck portions and one wabbler portion by 85 flowing molten metal upwardly within a suitable surrounding mold, and adding molten metal of a higher temperature from above within a supplemental wabbler mold, and maintaining surplus upper sinkhead 90 portions.

2. The process of manufacturing rolls of the class described, comprising flowing a molten metal upwardly within a suitable mold forming a main body portion, neck 95 portions and the lower wabbler portion, and flowing molten metal of a higher temperature downwardly through the supplemental mold forming an upper wabbler portion and sinkheads spaced from said upper wabbler 100 portion and connecting with the upper neck portion, substantially as and for the purposes described.

3. In casting metal bodies, the process of flowing molten metal upwardly within a 105 suitable mold to form a main body, and the addition of supplemental metal from above within a mold while the main body is still molten forming upper terminal and supply members, the supplemental supply members 110 connecting with the main body a substantial distance below the upper terminal, substantially as described.

4. In the manufacture of rolls of the class described, the formation of a main body, 115 neck portions and the lower wabbler portion by flowing molten metal upwardly within a suitable main surrounding mold, and adding molten metal, of a higher temperature, from above within a supplemental mold to 120 form the upper wabbler portion and sinkhead portions spaced from said upper wabbler portion and connecting with said neck portion at the base of the wabbler portion, substantially for the purpose described.

5. In the manufacture of rolls of the class described, the formation of a main body, neck portions and one wabbler portion by

flowing molten metal upwardly within a suitable surrounding mold, and adding molten metal, of a higher temperature, from above within a supplemental mold to form the other wabbler at the upper end and sink-head portions at the sides of said upper wabbler.

In testimony whereof I hereunto affix my signature in the presence of two witnesses.

HAROLD A. LOMAX.
